TROUSERS WAIST BAND CONSTRUCTION

David Arthur Blumberg, Baltimore, Md.

Application April 20, 1937, Serial No. 138,059

2 Claims. (Cl. 2—236)

This invention relates to trousers waist band construction and proposes a combination and arrangement of parts by which the wearer can adjust the trousers to have a high or low rise, the rise being the height of the trousers relative to the anatomical waist line.

One of the objects of the invention is to provide trousers having an integrally or permanently attached waist band, and a superposed waist band attachable and removable from the garment at will. The lower or permanent waist band may carry belt straps, while the detachable waist band may be furnished with means for attaching the suspenders.

Another object of the invention is to provide a removable waist band, detachably secured to the trousers by a circumferentially extending slide fastening device.

A further object of the invention is the provision of a removable waist band detachably secured by independent slide fasteners each extending semi-circumferentially from the front to back and each consisting of the conventional series of coordinating hooks, with the keeper at the front and the slide movable rearwardly to fasten the hooks. This arrangement makes it possible to alter the girth of the garment by taking in at the rear seam, cutting off as much of the terminal portions of the slide fasteners as may be required, without impairing the operation of the slide.

Other objects of the invention will appear as the following description of a preferred and practical embodiment of the invention proceeds.

In the drawing which accompanies and forms a part of the following specification and throughout the several figures of which the same characters of reference have been used to designate identical parts:

Figure 1 is a perspective view of trousers embodying the features of the present invention;

Figure 2 is a similar view showing the upper waist band removed;

Figure 3 is a front elevation of the upper portion of trousers illustrating the fly partly opened to disclose the rear construction, and showing the detachable waist band partially removed; and

Figure 4 is a section taken along the line 4—4 of Figure 3.

Referring now in detail to the several figures, the numeral 1 represents in general a pair of trousers having the customary unitary or integral waist band 2 and a superposed optionally removable waist band 3. It is generally conceded, meas-

ured by the standards of present-day vogue, that trousers with a high rise present a more dressy appearance than those with a low rise, notwithstanding which there are a great many people who find it convenient and comfortable to wear trousers with a high rise in connection with suspenders, but who would prefer a low rise waist band when wearing a belt.

Figure 1 shows the upper waist band 3 provided with buttons 4 on the inside for the attachment 10 of the suspenders 5, while the lower waist band 2 is provided with the belt straps 6. Just below the upper margin of the lower waist band 2 are sewn or otherwise secured the lower halves 7 and 8 of two independent slide fasteners 9 and 15 10. Along the lower margin of the removable waist band 3 are the cooperating parts 11 and 12 of the slide fasteners. Said slide fasteners extend circumferentially on either side of the trousers, the keepers 13, with cooperating prongs 20 13' by which the cooperating parts of the slide fasteners are initially brought together, being adjacent the fly opening, and the slides 14 are moved rearwardly in the act of bringing the parts of the slide fasteners together. The fact that 25 the lower parts of the slide fasteners are a little below the edge of the lower waist band bring the slide fasteners below the line of separation between the two waist bands and effectively conceal them from the outside of the garment. A flap 30 15 of fabric extends over the slide fasteners from the inside, concealing them.

In Figure 3 the flap 15 is shown broken away in the middle of the trousers so that the edges 16 and 17 of the upper and lower waist bands are 35 visible indicating that the waist bands are entirely separable one from the other when the slide fasteners are separated. Said slide fasteners extend to a position of substantial abutment at the rear of the garment, being separated only by a very 40 small space representing the width of the hem.

One of the advantages of this detachable waist band is that it may be applied or removed while the garment is being worn. It is removed by the wearer first undoing the top button or 45 so of the fly, reaching around to the rear, first on one side and then on the other grasping the respective slides and drawing them around to the front, thus completely unfastening each of the slides. To replace the waist band, it is necessary only to place the latch in the keeper at one side of the fly, then draw the slide to the rear, securing the parts of the slide fastener together, repeating this operation for the other side. Thus a man may start out wearing the 55

high rise waist band 3 with suspenders, and desiring to discard the suspenders in favor of a belt, he may detach the waist band 3 removing it together with the suspenders, transferring the 5 garment into a low rise garment with the belt 18 passing through the belt strap 6 as shown in Figure 2.

The arrangement of the slide fasteners in an independent pair with the keepers in front, permits alteration of the girth of the garment to 10 fit the size of the wearer by simply taking in material at the rear seam 19 in the usual manner cutting off as much of the adjacent portions 15 of the slide fastener as may be necessary to effect this shortening in the circumference of the waist band. The ends of the slide fasteners may be anchored by staples 20 or stitching and the severance of any portion of the ends thereof will not interfere in the least in the operation 20 of the slides 14.

While I have in the above description disclosed what I believe to be a preferred and practical embodiment of the invention, it will be understood to those skilled in the art that the 25 specific details as shown and described are merely by way of example and not to be construed as limiting the scope of the appended claims.

What I claim is:

1. In combination with trousers having a normal low rise waist band provided with belt straps 30 in the zone of said waist band, a high rise waist band adapted to be attached or detached with respect to said trousers at will, a pair of slide

fasteners extending in opposite directions circumferentially from adjacent points at the middle front of the trousers to adjacent points at the middle back of the trousers, the cooperating halves of the string pieces of said fasteners being secured to the respective adjacent edge portions of said trousers and waist band with the disengageable prong and keeper of each slide fastener at the front, whereby the slides move backward in a fastening direction, said string pieces being secured to the inside of said trousers and waist band with the line of separation between their halves out of alignment with the meeting edges of said trousers and waist band.

2. In combination, in a nether garment, a 1 waist band adapted to be attached or detached with respect thereto at will, a pair of slide fasteners extending in opposite directions circumferentially from adjacent points at the middle front of the garment to adjacent points at the 2 middle back of the garment, the cooperating halves of the string pieces of said fasteners being secured to respective adjacent edge portions of said garment and waist band with the disengageable prong and keeper of each slide fastener 25 at the front, whereby the slides move backward in a fastening direction, the string pieces being on the inside of the garment and waist band with the line of separation between the halves of said string pieces out of alignment with the meeting edges of the garment and waist band where- 30 by the slide fasteners are concealed.

DAVID ARTHUR BLUMBERG.
